UNITED STATES PATENT OFFICE.

GEORGE A. JOHNSON, OF CHICAGO, ILLINOIS, ASSIGNOR TO WILLIAM H. MINER, OF CHAZY, NEW YORK.

RAILWAY-CAR DRAFT-RIGGING.

1,223,794.

Specification of Letters Patent. Patented Apr. 24, 1917.

Application filed July 25, 1914. Serial No. 853,014.

To all whom it may concern:

Be it known that I, GEORGE A. JOHNSON, a citizen of the United States, residing at Chicago, in the county of Cook and State 5 of Illinois, have invented a certain new and useful Improvement in Railway-Car Draft-Rigging, of which the following is a full, clear, concise, and exact description, reference being had to the accompanying 10 drawings, forming a part of this specification.

This invention relates to improvements in railway car draft riggings and more particularly to the yoke employed therewith.

15 An object of the invention is to provide a draft rigging for railway cars employing a two piece yoke and having co-operative means on the yoke and a follower for preventing lateral separation of the yoke parts.

20 Another object of the invention is to provide a two piece yoke of novel and cheap construction and which is efficient in operation.

In the drawing forming a part of this 25 specification, Figure 1 is a side elevation of a portion of a draft rigging showing my improvements in connection therewith. Fig. 2 is a horizontal sectional view taken substantially on the line 2—2 of Fig. 1, the 30 yoke being shown in plan. Fig. 3 is a vertical sectional view taken substantially on the line 3—3 of Fig. 1 and Fig. 4 is a perspective view, upon an enlarged scale, showing the butt end of the coupler, a half of the 35 yoke and the front follower associated therewith.

In said drawing 10—10 denote the center sills or the draft members having the stop plates 11—11 secured to the inner sides 40 thereof, each stop plate being provided with front stop shoulders 12, rear stop shoulders 13, front intermediate stop shoulders 14 and rear intermediate stop shoulders 15. The stop castings are furthermore provided with 45 limiting stops 16 for all the followers. A designates the yoke which, as shown, comprises two like members 17—17. Each member 17 has upper and lower horizontally extending arms 18 and 19 connected at the 50 rear as at 20 and provided with a rear filler 21 and a connecting thimble 22, the latter being substantially channel shape in horizontal cross section. At its forward end each member 17 has its upper and lower 55 arms indented as indicated at 23, the free

ends of the arms being inturned as indicated at 24 to form front shoulders engaging the corresponding shoulders 25 on the rear end of the draw-bar 26. On their inner sides, the arms 18 and 19 are provided with oppositely and inwardly extended projections 27—27, these projections being so spaced from the gibs 24—24 that the enlarged coupler butt is adapted to be received therein, the back end of the coupler butt engaging the members 27—27. Each member 17 of the yoke is provided at its rear end with a hinge lug 28 and at its forward end with upwardly and downwardly extending ears 29, said hinge lugs 28 and ears 29 being 60 perforated as indicated at 30 to receive a bolt 31 therethrough, the bolt at the rear extending vertically and those at the front extending horizontally as clearly appears from Figs. 1 and 2. Mounted within the yoke is a front follower 32, intermediate followers 33 and 34, and rear follower 35, the followers having interposed therebetween springs 36 which may be of any well known or desirable construction. As shown, the front follower 32 is recessed on its upper and lower edges as indicated at 136 thus leaving upwardly and downwardly extending projections 37 at the four corners of the follower. The height of the central portion of 65 the follower 38 corresponds to the distance between the opposite ends of the members 27—27 so that the follower can be slipped in between said members of the yoke and the projections 37—37 will engage the outer 70 sides of said members 27. As shown in Fig. 1, the opposed faces or edges 39 of the members 27 are slightly flared to thereby facilitate the entrance of the portion 28 of the front follower thereinto upon relatively longitudinal movement between the follower and yoke. The followers, and hence the gear itself and yoke, are supported by straps 40 secured to the stop members by bolts or other suitable devices in any well known manner. It will also be noted, by inspection of Figs. 2 and 4, that the outer edges of the upper and lower arms of each draft yoke member is inclined as shown at 41.

In assembling the devices, the followers 45 105 33, 34 and 35 and the springs 36 are inserted in the usual manner and the front follower 32 is first inserted transversely through the yoke and then moved forwardly until positioned between the members 27—27 after 110

which the spring between said follower 32 and the front intermediate follower 33 can be inserted. Under buff, the draw-bar engages both the members 27—27 and the front 5 follower and compresses the front spring 36 against the follower 33, the rear spring being compressed in the usual manner through the intermediary of the follower 34 and intermediate yoke thimble. Under draft, the 10 followers 33 and 35 are moved forwardly compressing the springs against the followers 32 and 34, the latter remaining stationary. By employing a follower recessed or 15 cut away as applicant's front follower 32 and having the corner extensions thereof engaging portions of the yoke parts, said follower prevents the lateral separation of the two part yoke and the use of the bolted ears 29—29 may be optional. It will also be apparent that the use of a cut or notched follower, such as applicant's front follower 32, 20 is not necessarily confined to the front follower.

Although I have herein shown and described in detail one form of my invention, the same is merely illustrative and I contemplate all changes and modifications as come within the scope of the claims appended hereto.

30 **I claim:**

1. In a railway draft rigging, the combination with a yoke formed of two parts and divided centrally longitudinally, each 25 of said parts being in the form of a loop and having inwardly extending, opposed

projections, of a follower extending transversely through said yoke, said follower being cut away on its upper and lower edges, the narrow portion of said follower formed by said cut away portions being adapted to be seated between said inwardly extended projections formed on the yoke parts. 40

2. In a railway draft rigging, the combination with a yoke consisting of two parts, each part being in the form of a loop and 45 having opposed, inwardly extending projections near the forward end thereof, of a front follower extending through said yoke, said follower being cut away on the top and bottom edges thereof and adapted to be received between said inwardly extending projections on the yoke members. 50

3. In a draft rigging for railway cars, the combination with a two-part yoke, the parts being separable and having a division line 55 extending longitudinally and centrally thereof, said yoke parts when assembled having a hood at the forward end thereof within which is adapted to be received a butt of a standard draw bar, said yoke being provided with downwardly and upwardly projecting flanges at the rear of said hood and against which the rear face of the draw bar butt is adapted to bear, of an H-shaped follower extending transversely through the 60 yoke and adapted to fit between said flanges. 65

GEORGE A. JOHNSON.
